UNITED STATES PATENT OFFICE.

WILLIAM P. CUMMINGS, OF LONG ISLAND CITY, NEW YORK.

BUILDING CONSTRUCTION.

Application filed November 30, 1923. Serial No. 677,773.

To all whom it may concern:

Be it known that I, WILLIAM P. CUMMINGS, a citizen of the United States of America, and a resident of Long Island City, in the county of Queens and State of New York, have invented a new and Improved Building Construction, of which the following is a description.

My invention relates to the construction of cement walls and the general object of the invention is to provide a method of producing a cement wall utilizing pre-cast posts and run-in-place walls between the posts.

A further important object of the invention is to provide a method of constructing cement walls, whereby the wall may be accurately built and done for the major portion by unskilled labor.

The nature of the invention, its distinguishing features and advantages will more clearly appear as the description proceeds.

Reference is to be had to the accompanying drawings forming a part of this specification, it being understood that the drawings are merely illustrative of one example of the invention.

Figure 1 is a view partly in section and partly in elevation of a wall in the course of construction in accordance with my invention;

Figure 2 is a horizontal section as indicated by the line 2—2, Figure 1;

Figure 3 is a vertical section in the plane indicated by the line 3—3, Figure 1, and showing a portion of a run-in-place wall;

Figure 4 is a fragmentary elevation showing the manner of disposing the posts in the construction of a wall in successive stories.

In carrying out my invention in practice a footing 10 of cement is laid and in the said footing small standards 11 are cast and project above the surface of the footing. The standards 11 are disposed in pairs and the pairs are spaced apart a distance to snugly receive between the pairs the pre-cast cement posts 12. The posts 12 have transverse strips 13 molded therein flush with the opposite side faces of the posts and when the posts are in position said strips 13 are crossed by the standards 11 and said standards are then nailed to the strips to hold the posts 12 centered. As is customary in cement wall construction the posts 12 have incorporated therein transverse rods 14 projecting slightly beyond the opposite side faces of the posts for the wiring thereto of

reinforcing material indicated at 15 which thus extends substantially from post to post and is anchored to the posts by the rods 14.

The pre-cast cement posts 12 are formed with vertical series of transverse bolt holes 16 extending through the posts from front to rear. Said holes are adapted to receive bolts 17 for securing to the posts mold boards 18 at opposite faces of the posts, whereby said posts with the footing 10 complete the mold for the pouring of a run-in-place wall 19 between each pair of posts 12. The pouring of the run-in-place walls 19 causes the same to firmly adhere to and unite with the footing 10 and pre-cast posts 12. The constructing of the mold and the pouring of the walls, as well as the provision for positioning and centering the posts 12 on the footing 10 to contribute to enabling my improved wall to be formed by using unskilled labor to the maximum extent, skilled labor only being required for the positioning of the posts, the positioning of the window frames, one of which is indicated at A, and the securing of the bottom mold boards 18. The window frames may readily and accurately be positioned with my construction because they may find support on the mold boards 18. Accuracy is insured simply by properly positioning the posts after which the erecting of the mold and the pouring of the walls make it practically impossible for an unskilled laborer to do otherwise than to properly mold a wall.

In Figure 4 I have shown in connection with the top-story and the posts for the second story, the same mode of centering the posts 112 by the centering pairs of standards 111 corresponding with the standards 11 molded in the wall 19 at the top to extend above the same and spaced to accommodate the posts 112 for the second story, said posts having transverse strips 113 corresponding with the strips 13 and having transverse bolt holes 116 corresponding with the holes 16.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. In a method of cement wall construc-

- tion; forming separate pre-cast posts with vertical series of transverse bolt holes therein, erecting said posts in positions spaced from one another, securing mold boards to said posts by passing bolts through said mold board and said bolt holes, and running cement between said mold boards and extending from the one post to the next post and in intimate contact with said posts.
- 10 2. In a method of cement wall construction; laying a wall footing, erecting on said footing pre-cast posts having vertical series of transverse holes therein, securing mold boards to the front and back of said pre-cast posts by passing fasteners through said mold boards and said holes, and pouring cement to form walls between said boards and extending from post to post in union with said posts.
- 15 3. In a method of cement wall construction; laying a footing, and incorporating

therein standards rising above the footing, positioning pre-cast posts adjacent to said standards, fastening said posts to said standards, affixing mold boards directly to said posts at the back and front, and pouring cement to form a wall between said boards and into intimate union with said pre-cast posts.

4. In a method of cement wall construction; laying a footing and incorporating 30 therein standards rising above the footing and disposed in pairs spaced to snugly accommodate posts between the standards of each pair, positioning pre-cast posts between the standards of each pair and fastening 35 said posts to said standards, affixing mold boards directly to said posts at the front and back, and pouring cement to form a wall between said boards and into intimate union with said pre-cast posts and said footing.

WILLIAM P. CUMMINGS.
